Primary Examiner—Cathron Brooks*Assistant Examiner*—Angela J Lee(74) *Attorney, Agent, or Firm*—Novak Druce + Quigg, LLP(57) **CLAIM**

The ornamental design for a handheld device, as shown and described.

DESCRIPTION

FIG. 1 is a front elevational view of a handheld device depicting our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a perspective view thereof.

The broken lines shown in the bottom central portion of FIGS. 1 and 7 represent an unclaimed area up to but not including the circular member illustrated by the solid line, while all other broken lines on FIGS. 1-7 are directed to environment and are for illustrative purposes only; the broken lines form no part of the claimed design.
